BURNER FUEL PIPE CLEANER

Clarke T. Welsh, Logansport, Ind.

Application June 26, 1941, Serial No. 399,867

4 Claims. (Cl. 158—120)

This invention relates to fuel pipe cleaners for liquid fuel burners and more particularly to an automatically actuated cleaner for the fuel pipe and fuel flow passage of a liquid fuel burner which operates periodically to prevent the accumulation of any obstruction to fuel flow.

The advantages of periodic automatic cleaning of the fuel supply passage of a pot or gravity feed type of burner are more than the insurance of uniform and proper operation of the burner by preventing obstruction of the fuel flow. The periodic cleaning makes possible the use of cheaper grades of fuel in gravity feed or pot type burners which are generally only satisfactory for the gun type or pressure feed burners. The cheaper grades of fuels generally contain more substances which tend to separate from the fuel and accumulate in or near the end of the fuel supply line, thereby to obstruct and interfere with the continued flow of fuel to the burner. The present invention prevents this interference with normal fuel flow, even with the cheaper fuels, and effects movement of the obstructing substances to a place in the burner pot where they are burned.

An object of this invention is to provide an automatically actuated cleaner for the fuel flow passage of a liquid fuel burner which periodically removes any accumulated substances from the fuel flow passage and moves them to a place in the burner where they are burned.

Another object of this invention is to provide a cleaning device for the fuel flow passage of a liquid fuel burner which makes possible the use, in a gravity feed or pot type burner, of fuel of a lower grade than that ordinarily used in such burners.

Another object of this invention is to provide a cleaning device for the fuel feed passage of a liquid fuel burner which moves obstructing substances from said passage to a place within the burner at which they will be burned.

Another object of this invention is to provide a cleaning device for the fuel feed passage of a liquid fuel burner which does not materially obstruct normal flow of fuel due to the adherence of substances to the cleaning element.

Another object of this invention is to provide a cleaning device for the fuel feed passage of a liquid fuel burner which is automatically timed for periodic operation.

Other objects and advantages of this invention relate to various features of construction and arrangement of parts which will be apparent from

a consideration of the following specification and accompanying drawing, wherein

Figure 1 is a side sectional view of apparatus embodying a preferred form of the present invention; and

Figs. 2, 3, 4 and 5 are sectional views taken substantially on the lines 2—2, 3—3, 4—4 and 5—5, respectively, of Fig. 1 and in the directions indicated by the respective arrows.

Having particular reference to the drawing, the apparatus which comprises the present invention is illustrated as being adapted to a pot type or gravity feed oil burner, although it is not necessarily limited thereto. A burner pot 10 such as that commonly used and well-known in the oil burner field has connected thereto and communicating therewith a straight section of pipe 12 threaded into a coupling 13 on the burner pot at one end and connected through a T-type coupling 14 to a fuel feed line 15, so that the pipe 12 comprises a part of the fuel feed line. The fuel feed line 15 is preferably provided with a constant level valve which is indicated at 16 to control the flow of fuel through the fuel feed line 15.

As a general rule, the gravity feed or pot type burners require a higher grade or better quality of fuel than that required by some other types of burners. This makes the usual fuel somewhat more expensive than the lower grades of fuel. The lower grades of fuel contain more residue and substances which tend to separate out and deposit in the fuel feed line, particularly in the portion of the fuel feed line near the burner pot. Even the higher grade fuels deposit some residue in the fuel feed line near the burner pot so that the line should be cleaned at intervals. In the present invention, a mechanism is provided for intermittently or periodically cleaning the portion of the fuel feed line near the burner pot.

To accomplish this cleaning of the fuel feed line, a shaft or cleaner rod 17 of considerably smaller diameter than the internal diameter of the straight pipe 12 extends through the T-type coupling and into the pipe 12. This cleaning rod or shaft 17 has cleaning blades 18 thereon and preferably integrally formed therewith. The cleaning blades 18, 19 and 20 have relatively sharp edges which conform to and fit the interior surface of the pipe 12. The cleaning blades are preferably segmental and are circumferentially staggered to leave clearance for the passage of fuel through the pipe 12 and to minimize the collection of deposited residue between

adjacent blades. The longitudinal spacing of the blades along the shaft 17 also assists in minimizing the collection of residue therebetween. The surfaces of the blades facing the burner pot are preferably substantially perpendicular to the longitudinal axis of the shaft 17; while the opposite surfaces thereof are preferably tapered to an extent such that the intersecting surfaces form an acute angle. The perpendicular front surfaces push any accumulated residue into the burner pot upon longitudinal movement of the shaft 17 in one direction and the tapered rear surfaces tend to prevent catching or sticking of the blades in an abnormal position near or within the burner pot.

The end of the shaft 17 opposite the cleaning blades projects from the pipe 12 and the T-type connector 14 through a housing comprising a section of pipe 22, a coupling 23 and a second section of pipe 24 which is preferably brass or non-magnetic material. The end of the shaft 17 is secured to a connecting unit 25 of brass or other suitable non-magnetic material, as by being threaded thereto. A key 26 is preferably provided on the shaft 17 which extends longitudinally therealong and is slidable in a keyway 27 in a partition 28, which partition is preferably secured within the coupling 23. This key and keyway prevent turning of the cleaning rod within the pipe 12.

The end of the non-magnetic connecting unit 25 opposite the shaft 17 is threaded into, and thereby secured to one end of an armature or magnetic core 29 of a solenoid 30.

The armature or core 29 is slidable longitudinally within the pipe 24 and is normally biased by a spring 32 to a position offset from the magnetic center of the solenoid. The spring 32 is secured to the end of the armature by a screw 33 or other suitable fastening means and is anchored to a cap 34 on the end of the pipe 24 by a bolt 35 and cooperating nut 36.

The solenoid 33 has a winding 37 and insulating end supports 38 and 39. One end of the solenoid winding is connected through a lead 40 to a suitable source of energizing potential. The other end of the solenoid is connected to the source of energizing potential through a timing switch 42 and preferably through a fuse 43. The timing switch may be any suitable switch for intermittently or periodically energizing the solenoid for short intervals of time at suitable or desired intervals, such as a switch actuated by an electric clock. Energy for the operation of the clock or timing mechanism of the timing switch 42 is provided through a lead 44 and through the lead 45 which also carries the energizing current for the solenoid winding 37. The solenoid 30 and the timing switch 42, as well as the connections thereto are preferably enclosed within a housing 46 having a partition 47 therein which separates the solenoid from the timing switch. Suitable grommets such as 48, 49 and 50 are provided for the protection of the connecting leads where they extend through the metallic walls of the housing 46 and the partition 47.

In the preferred installation of the disclosed fuel pipe cleaner, the constant level valve and the size of the pipe 12 are such that the level of the fuel in the pipe 12 preferably stays below the opening in the partition 28 through which the shaft 17 extends. This prevents fuel from the feed line from getting into the solenoid armature chamber within the pipe 24, although no

particular harm should result from overflow of fuel oil past the partition 28 into the armature chamber. The section of pipe 12 adjacent the burner pot is preferably straight and the cleaner blades are disposed therein a short distance from the entrance to the burner pot when in the retracted or normal position which is illustrated. Energization of the solenoid attracts the center of the armature 29 to the magnetic center of the solenoid coil 37 against the biasing force of the spring 32 and thereby moves the cleaning blades 18, 19 and 20 in the pipe 12 and preferably to a position such that all of the blade segments are within the burner pot. By moving the cleaning blades into the burner pot, the residue moved thereby from the fuel pot 12 is pushed into the hot burner pot where it is burned along with the remainder of the fuel.

Although the solenoid may be manually energized at suitable or desired intervals, the provision of the timing switch 42 makes the energization automatic and periodical. Through the use of this cleaning device which periodically or intermittently cleans the portion of the fuel line near the burner pot, the lower grades of fuel than those normally useable may be used in the burner without effecting the usual clogging of the fuel feed line. By any system of energization, the solenoid need only be energized for a very short interval of time to effect the actuation and full longitudinal movement of the cleaning rod and blades. Upon deenergization of the solenoid, the armature, cleaning rod and the blades are retracted to their normal positions by the spring 32.

While an embodiment of the invention has been shown and described for the purpose of illustration, the applicant does not wish to be restricted specifically thereto since various modifications may be made without departing from the spirit of the invention.

What is claimed as new and upon which it is desired to secure Letters Patent of the United States is:

- 45 1. In combination with a pot type liquid fuel burner having a burner pot and a fuel feed line including a straight section of pipe connected to the burner pot, an automatic cleaning device comprising a cleaner rod of smaller diameter than the internal diameter of the straight section of pipe and having longitudinally spaced and circumferentially staggered cleaning blade segments thereon which fit into the inside of the straight section of pipe, said rod extending into the straight section of pipe to a position such that the cleaning blade segments are normally spaced from the burner pot, means preventing turning of the rod with respect to said pipe, a spring biasing the rod to said position in which the cleaning blade segments are spaced from the burner pot, an armature secured to the cleaner rod, a solenoid for actuating the armature to drive the rod toward the burner pot against the biasing force of the spring to a position such that the blade segments are moved to positions within the pot beyond the straight section of pipe, and automatic timing means effecting periodic energization of the solenoid for short intervals of time.
- 50 2. In combination with a gravity feed type of liquid fuel burner having a burner pot and a fuel feed line including a straight section of pipe connected to the burner pot, a fuel line cleaner comprising a cleaner rod of smaller diameter than the internal diameter of the straight

- 75

section of pipe and having segmental cleaning blades thereon which fit into the inside of the straight section of pipe, said rod extending into the straight section of pipe to a normal position such that the cleaning blades are located intermediate the ends of the straight section of pipe, resilient means biasing the rod to said normal position, magnetically actuated means for moving the rod axially within the straight section of pipe through a range such that the cleaning blades are moved from the pipe into the pot for removing deposited material from the pipe into the pot, and automatic means effecting intermittent energization of the electromagnetic means.

3. A gravity feed type liquid fuel burner comprising a burner pot, a duct provided at one end with a straight pipe section communicating with the pot for delivering liquid fuel thereto and provided adjacent the other end with an armature casing section, a liquid fuel supply conduit communicating with said pipe for supplying fuel to the pot, electromagnetic means comprising an armature within said casing, and pipe cleaning means attached to said armature and operable thereby comprising a reciprocable rod within said duct provided with pipe scraping means reciprocable between positions within

said pipe and positions within said pot for effecting removal into the pot of material deposited within the pipe by fuel flowing through the latter into the pot.

- 5 4. A gravity feed type liquid fuel burner comprising a burner pot, a duct comprising a straight horizontal pipe section at one end thereof communicating with said pot for delivering fuel thereto and an armature casing section adjacent 10 the other end, a reciprocable rod within said duct provided with pipe scraping means adjacent the outlet end of said pipe section, electromagnetic means comprising an armature within said casing section and connected to said rod for reciprocating the latter periodically for moving said scraping means through said outlet end of the pipe into the pot for removing deposited material from the pipe and depositing same within the pot, a fuel supply conduit communicating with said pipe section for delivering liquid fuel to the latter, and a member in said duct between the junction thereof with said supply conduit and said armature casing section and provided with a guiding aperture for said rod and 20 constituting a barrier to the flow of fuel into the armature casing section of said duct.
